RECEPTACLE

Filed Jan. 3, 1929

UNITED STATES PATENT OFFICE

ARTHUR VON FRANKENBERG, OF NEW YORK, N. Y.

RECEPTACLE

Application filed January 3, 1929. Serial No. 330,044.

This invention relates to receptacles. More particularly it is directed to a water tight container for cigarettes and the like.

Among the objects of this invention is to provide a neat, compact and rugged receptacle of the character described which shall comprise few and simple parts, which shall be relatively inexpensive to manufacture, easy to open and close and yet be positively water-proof, and practical and efficient to a high degree.

Other objects of this invention will in part be obvious and in part hereinafter pointed out.

15 The invention accordingly consists in the features of construction, combinations of elements, and arrangement of parts which will be exemplified in the construction hereinafter described, and of which the scope of 20 application will be indicated in the following claims.

Certain features herein shown and described are shown, described and claimed in my copending application Serial No. 330,042 25 filed in the United States Patent Office on the 3rd day of January, 1929, and accordingly are not claimed herein.

In the accompanying drawing, in which is shown one of the various possible illustrative 30 embodiments of this invention:

Fig. 1 is an elevational, cross-sectional view of a receptacle embodying the invention;

Fig. 2 is a cross-sectional view taken on line 2—2 of Fig. 1;

35 Fig. 3 is a cross-sectional view taken on line 3—3 of Fig. 1;

Fig. 4 is a perspective view of a detail;

Fig. 5 is a partial cross-sectional view of a modified construction taken on line 5—5 of 40 Fig. 6; and

Fig. 6 is a cross-sectional view taken on line 6—6 of Fig. 5.

Referring in detail to the drawing 10 designates a water tight receptacle embodying 45 the invention, in the form of a cigarette case adapted to be used by persons while bathing and for like purposes. Said receptacle comprises, generally, an inner box or container 11 for cigarettes and the like, an outer jacket 50 or cover member 12, a sealing member 13 for

said container, and mechanism 14 for retaining said sealing member in position for rendering said container water tight.

The inner box 11 comprises a bottom wall 15, front and rear walls 16 and side walls 17, and is preferably of such size as to snugly receive the usual package of cigarettes 18, thru the upper open end portion 19 thereof. Said open end portion 19 presents an edge 20 adapted to contact with the sealing member 13 for water proofing the container. The length of the inner box 11 is preferably somewhat greater than that of the usual cigarette package. Received in said box is a U-shaped member 21 which serves as a holder for said package. Said member 21 comprises an intermediate portion on which said package 18 is seated, and upwardly extending side arms 23 adapted to engage the sides of said package. Interposed between said member 21 and the bottom wall 15 of box 11 is a curved plate spring 24 normally maintaining the upper edges 25 of said arms 23 pressed against the under side of the sealing member 13 for a purpose hereinafter appearing.

The outer jacket or cover 12 is open at the bottom end thereof for receiving the box 11, and comprises a top wall 28, side walls 29 and front and rear walls 30. At the bottom open end portion thereof, said front, rear and side walls are provided with an inturned portion 31 forming a guide wall 31^a adapted to loosely fit about the sides of the box 11. The side walls 29 of said jacket are preferably spaced from the side walls 17 of box 11 to provide chambers 32 on opposite sides of said box. The top wall 28 of the cover, as seen in Fig. 1, may be rounded and spaced from the top edge 20 of box 11 to provide a chamber 33. Housed within said chambers 32, 33 is the mechanism 14 which cooperates with the sealing member 13 for rendering the container 11 water tight.

Said mechanism 14 comprises a pair of symmetrical strips 34, 35 preferably made of resilient metal, and secured at the lower ends 34^a, 35^a thereof, respectively, as by soldering or by rivets 27 to the inner surfaces of side walls 29. Said strips 34, 35 are formed with intermediate inwardly bent portion 34^b, 35^b.

respectively, and are bent inwardly at the upper ends thereof, to form extensions 34^c, 35^c projecting into chamber 33. Said strips are further formed with inwardly stamped hook portion 36, 37 adapted to engage complementary hook portion 36^a, 37^a stamped outwardly from the side walls 17 of box 11. It will be now apparent that when box 11 is inserted into the jacket 12 thru the open end of the latter, and said box is pushed thereinto to a distance sufficient for the hook portion 36, 37 to interengage hook portion 36^a, 37^a respectively, the edge 20 of said box will then be retained against the under surface of sealing member 13, the spring strips 34, 35 normally pressing inwardly to keep said hook portions interlocked.

The sealing member 13 is preferably made of soft resilient material such as rubber. Mechanism 14 is provided with means for tightly pressing said member 13 down against said edge 20 to render said box 11 positively water-tight. To this end a plate 40 preferably of metal is superimposed on the resilient member 13, and is provided with aligned notches or slots 42 at the opposite ends thereof adapted to receive and permit reciprocation of the free ends 34^c, 35^c of strips 34, 35. Mounted for rotation in suitable aligned bearings formed in walls 30 of the jacket 12, is a shaft 43 extending between the free ends 34^d, 35^d of portions 34^c, 35^c, respectively. One of said walls 30 is depressed as at 44 for receiving an actuating handle 45 secured to a projecting portion 46 of said shaft, for rotating the latter. Splined to said shaft 43, as by a pin and slot connection 47, is a cam member 48 adapted to press down on plate 40 when the handle 45 is in closing position, as shown in Figs. 1, 2 and 3. Loosely mounted on said shaft 43 is a one-way ratchet member 49 having a plurality of cammed teeth 50 adapted to coact with said free end portions 34^d, 35^d, in a manner hereinafter appearing. Said ratchet 49 is further provided with inclined teeth 51 adapted to engage and coact with the complementary teeth 52 on the cam member 48, said teeth 51, 52 forming a one-way clutch connection between said members 48 and 49. A small coil compression spring 53 received on said shaft 43, presses against member 49 normally forcing the same against member 48.

The operation of the device will now be clear. Figs. 1, 2, and 3 show the receptacle in closed condition. In the position shown, the hook portions 36, 37 and 36^a, 37^a, are interengaged, the sealing member 13 is pressed down by cam 48 and the free end portions 34^d, 35^d press against the inner portions 54 of the cam surfaces 55 formed on said teeth 50. In this position the container 11 is positively water tight. To open the receptacle for obtaining a cigarette or the like, it is merely necessary to lift the handle 45. Dur-

ing this operation, the cam 48 turns clockwise, looking at Fig. 1, to release the pressure from the plate 40 and sealing member 13, the ratchet member 49 being simultaneously rotated due to the clutch 51, 52. The rotation of said ratchet causes the opposite pair of cammed teeth 50 which contact the free ends of the strip 34, 35, to spread said strips. This spreading movement of the strips causes the hooks 36, 37 and 36^a, 37^a to disengage and release the container 11.

Should the handle 45 be given a full quarter of a turn during the releasing operation, the teeth 50 which press against the ends 34^d, 35^d of the strips, will ride past said strips, allowing said ends to snap inwardly against the low portions 54 of the next adjacent teeth. In such case, return, or counter-clockwise movement of the handle 45 to closing position will not rotate the ratchet member 49 in counterclock direction, since such rotation is prevented by reason of the engagement between said end portion 34^d, 35^d and the radial edges 58 of said teeth 50. During such counterclockwise movement of the handle, the member 49 will be forced toward the rear wall 30, looking at Fig. 3, against the pressure of spring 53, by the inclined teeth 52 of member 48 which contact with the teeth 51 of said member 49. When the handle 45 has been pushed back to its original closing position, the teeth 52 will have moved past the teeth 51 which they engage and permit the ratchet member 49 to snap back into place under the action of the compression spring 53.

Upon lifting the handle to disengage the hooks 36, 37, 36^a, 37^a, as described above, the box 11, due to its weight and also to the action of the plate springs 24, will move out thru the bottom opening of the jacket. It will be noted that when said box is about half way out of the jacket, the hooks 36^a, 37^a will strike the inwardly bent portions 34^b, 35^b respectively of the strips 34, 35, and then prevent the box from falling out of the jacket 12, should the person using the receptacle hold the jacket with one hand and operate the handle 45 with the other hand. When the box has thus been stopped half way out of the jacket, it may easily be grasped and pulled out by the hand which having operated the handle is now free.

To close the receptacle after use, it is merely necessary to reinsert said box 11 within the jacket 12 and push the box inwardly until the hooks 36, 37 and 36^a, 37^a interlock. The handle 45 may then be turned back to the position illustrated in Fig. 3, thus causing the cam 48 to press down on plate 40 and sealing member 13 to render the container 11 water tight.

Figs. 5 and 6 illustrate a modified construction of the mechanism for spreading the spring strips to disengage the interlocking hooks. In accordance with this modification

the spring strips 70 and 71 are formed with notches 70^a and 71^a. Secured to each strip as by soldering is a rod 73 extending thru the notch in the opposite strip. Said rods extend thru openings 74 in the opposite walls 75 of the jacket 12^a. A pair of coil compression springs 76 are interposed between the top wall 28^a of said jacket and plate 40^a which overlies the sealing member 13^a. Inward pressure on the free ends 78 of said rods will spread the strips 70 and 71 to disengage the hooks 80 and release the box 11^a. The springs 76 press down on the sealing member 13^a to effect the waterproofing of said box.

15 It will thus be seen that there is provided a device in which the several objects of this invention are achieved, and which is well adapted to meet the conditions of practical use.

20 As various possible embodiments might be made of the above invention, and as various changes might be made in the embodiment above set forth, it is to be understood that all matter herein set forth or shown in the accompanying drawing is to be interpreted as 25 illustrative and not in a limiting sense.

Having thus described my invention, I claim as new and desire to secure by Letters Patent:—

30 1. In a water tight receptacle, in combination, a container having an open end, a cover for said container, a sealing member and means for clamping said member to said container at said open end, said means comprising means for fixing said cover to said container, a shaft rotatably mounted on said cover and means to actuate said shaft extending on the outer side of said cover.

2. In a water tight receptacle, in combination, a container having an open end, a cover for said container, a sealing member and means for clamping said member to said container at said open end, said means comprising means for fixing said cover to said container, a shaft rotatably mounted on said cover and means to actuate said shaft extending on the outer side of said cover, said cover being recessed to receive said actuating means.

30 3. In a water tight receptacle, in combination, a container having an open end, a cover for said container, a sealing member and means for clamping said member to said container at said open end, said means comprising means for fixing said cover to said container, a shaft rotatably mounted on said cover, and a cam fixed for rotation with said shaft adapted to contact with said member.

4. In a water tight receptacle, in combination, a container having an open end, a cover for said container, a sealing member and means for clamping said member to said container at said open end, said means comprising means for fixing said cover to said container, a shaft rotatably mounted on said cov-

er, a cam fixed for rotation with said shaft, and a second cam member loosely mounted on said shaft.

5. In a water tight receptacle, in combination, a container having an open end, a cover for said container, a sealing member and means for clamping said member to said container at said open end, said means comprising means for fixing said cover to said container, a shaft rotatably mounted on said cover, a cam fixed for rotation with said shaft, a second cam member loosely mounted on said shaft, and clutch means interconnecting said cam members.

6. In a water tight receptacle, in combination, a container having an open end, a cover for said container, a sealing member and means for clamping said member to said container at said open end, said means comprising means for fixing said cover to said container, a shaft rotatably mounted on said cover, a cam fixed for rotation with said shaft, a second cam member loosely mounted on said shaft, clutch means interconnecting said cam members, and tension means normally maintaining said cam members interengaged.

7. In a water tight receptacle, in combination, with a container having an open end, a jacket adapted to fit over said container, means connected to said jacket adapted to interengage a portion of said container, means for sealing said container, and means for simultaneously disengaging said engaging means, and unsealing said container, said means comprising a pair of cam members connected by clutch means.

8. In a water tight receptacle, in combination with a container having an open end, a jacket adapted to fit over said container, means connected to said jacket adapted to interengage a portion of said container, means for sealing said container, and means for simultaneously disengaging said engaging means and unsealing said container, said means comprising a pair of cam members connected by clutch means, a single means for actuating said members from the outside of said cover, and resilient means normally pressing said cam members together.

In testimony whereof I affix my signature. 115
ARTHUR VON FRANKENBERG.
